UNITED STATES PATENT OFFICE.

AUGUST WILL, OF JERSEY CITY, NEW JERSEY, ASSIGNOR TO DAVID WOLFE BRUCE, OF NEW YORK, N. Y.

DESIGN FOR A FONT OF PRINTING-TYPE.

SPECIFICATION forming part of Design No. 12,644, dated December 27, 1881.

Application filed November 17, 1881. Term of patent 14 years.

To all whom it may concern:

Be it known that I, AUGUST WILL, (assignor to DAVID WOLFE BRUCE,) of Jersey City, Hudson county, New Jersey, have invented and produced a new and original Design for a Font of Printing-Type, of which the following is a specification.

The nature of my design is clearly shown in the accompanying typographic impression, to which reference is had; and it consists of an ornamented letter in which one of the up-and-down portions is composed, so to speak, of two sections, each composed of short parallel vertical lines with a space between them, the bottom and top portions of the sections connected about centrally by the short inclined lines crossing each other. These sections are left open at top and bottom, and the left-hand line is extended upon the left in a nearly horizontal line.

The character of the design is followed in the rounding portions of the letters, which are shaded, the shading being placed so that a space falls between it and the rounding portion of the letter.

In some of the letters—the A, E, and F—a rhombic ornament, with open space in center, is employed.

The character of the design is preserved in the symbols and numerals, as shown.

Having now described my invention, what I claim as new is—

The design for a font of printing-type, as shown and described.

AUGUST WILL.

In presence of—

WILLIAM V. H. HICKS,
A. SIDNEY DOANE.
